UNITED STATES PATENT OFFICE.

HENRY S. HALE, OF PHILADELPHIA, PENNSYLVANIA.

CAR-SEAT.

SPECIFICATION forming part of Letters Patent No. 741,033, dated October 13, 1903.

Application filed January 14, 1903. Serial No. 138,979. (No model.)

To all whom it may concern:

Be it known that I, HENRY S. HALE, of the city and county of Philadelphia, State of Pennsylvania, have invented an Improvement in 5 Car-Seats, of which the following is a specification.

My invention has reference to car-seats; and it consists of certain improvements which are fully set forth in the following specification and shown in the accompanying drawings, which form a part thereof.

My invention has for its object certain improvements in that class of car-seats in which the back is reversible by being guided from one side of the seat-frame to the other without revolving on the pivot, and, more specifically, the objects are to cause the seat-back to be elevated upon its supporting devices to a greater extent when in its middle position than at its extreme position, so that greater clearance between the bottom of the seat-back and the seat-cushion is secured during the reversing operation; also to so arrange the parts that the seat-back may be fitted close to the seat-cushion at its extreme positions and wholly clear the cushion while being reversed; also to reduce the weight upon the end guides which support the seat-back in its extreme position at a time when said seat is being shifted between said extreme positions, so as to make the reversal of the car-seat more easily performed, and to secure other advantages referred to hereinafter.

In carrying out my invention I provide the ends of the seat-frame with transverse guides, preferably somewhat curved, and upon these are arranged guide-brackets which support the weight of the seat-back in its extreme position and steady it during transition, and in the preferred form of my invention said brackets are provided with radial guide-arms adapted to sockets in the seat-back and upon which said back is guided in its vertical adjustment. Combined with the foregoing parts are rocker-arms pivoted to the end frames and jointed at their upper ends to the bottom of the seat-back, preferably by detachable bearings, whereby the curvature of the arc traveled by said upper ends of the 50 rocker-arms is greater than the curvature traveled by the brackets, so that in the travel

of the brackets and seat-back from one side of the seat to the other the seat-back is bodily elevated by the rocker-arms to such a degree as to be materially elevated upon the brackets at the intermediate portion of their travel. 55

My invention insures greater ease in taking off or detaching the backs of car-seats, and they may be locked or non-detachable except when raised to intermediate position 60 in reversing.

My invention also comprehends adjustable lids or plates arranged on each end of the seat structure and adapted to close the space intermediate between the seat-cushion and the end frames of the seat, said adjustable portions being adapted to be raised automatically by and to permit the travel of the guide-brackets and rocker-arms. 65

My invention also comprehends minor features of construction, which, together with those above mentioned, will be better understood by reference to the drawings, in which— 70

Figure 1 is a transverse sectional elevation on line xx of Fig. 2 adjacent to one end of the seat and with the cushion and back indicated in dotted lines. Fig. 2 is a vertical longitudinal section on line yy of Fig. 1 through the seat when the seat-back is in its intermediate position. Fig. 3 is a perspective view of one of the seat-back supporting and guiding brackets. Fig. 4 is a perspective view showing the construction of the hinge-joint between the seat-back and rocker-arms, and Fig. 5 is a cross-section showing 85 the adjustable shielding-lids between the seat-cushion and end frames.

A represents the end frames and are provided with the curved guides A'. These end frames are connected together by the longitudinal bars B, as usual. 90

C represents rocker-frames for carrying the seat-cushion C' and have the cam-surfaces C', adapted to rest upon the socket parts B', extending from the end frames and receiving 95 the bars B. The shifting of these rocker-frames causes the seat-cushion to be shifted and also tilted in the usual manner.

D' is a rocker-shaft pivoted between the end frames A and has secured to it the rocker-arms D, which are extended below and provided with lateral pins d, extending into ver- 100

tical slots *c* in the rocker-frames *C*, so that when the said rocker-arms *D* are oscillated the seat-cushion is rocked and tilted.

E represents sliding brackets having the 5 guides *e*, adapted to the curved guides *A'* and at their upper ends extended laterally and then upward in a long guide-arm *E'*, which fits into holes or apertures *l* in the frame of the seat-back *L*. The upper ends of the 10 rocker-arms *D* extend through openings *E*² in the sliding brackets and are provided with sockets *f* and lateral pins *H*, the latter being adapted to slots *h* in the guide-arms *E'*, so that when the sliding brackets are moved the 15 rocker-arms *D* are moved also. The moving of these rocker-arms performs two results—namely, the shifting of the seat-cushion and the elevating of the seat-back *L* as it is shifted toward a vertical line (dotted lines, Fig. 1) 20 and its subsequent lowering. This latter result is accomplished by providing the lower corners of the seat-back with heel-plates *G*, having bearings *F* adapted to the sockets *f* in the upper ends of the rocker-arms *D*, Fig. 4. 25 These heel-plates also have slots *g*, through which the guide-arms *E'* pass and are guided.

It will now be understood that by pushing over the seat-back *L* in reversing the seat the sliding brackets *E* are moved over 30 their guides *A'*, and at the same time the rocker-arms *D* are rocked. As the arcs described by the ends of these arms *D* have a shorter radius than that of the curved guides *A'* and as the fulcrum-point *D'* of the said 35 arms *D* is higher than the center of curvature of the guides *A'*, it is evident that the effect of said arms is to elevate the seat-back upon its guide-arms *E'* in the act of reversing the seat-back and then lower it down again in 40 completing its travel. In this way great clearance is secured between the seat cushion and back. A guide *A'* of less curvature may be employed, and much of the weight and friction is removed from the guides *A'* and transferred to the rock-shaft. This latter results 45 in a more perfect action and easy manipulation in reversing the back. The durability of the seat is increased, wear on the upholstery is much reduced, and the back is enabled to fit down close to the seat-cushion in 50 its extreme positions, while clearing it in all others. The seat-cushion may also be given greater curvature and spring action, because of the greater clearance of the seat-back in 55 passing over its middle portion which is possible.

The curvature of the guide *A'* is only required to be just sufficient to give the proper obliquity to the seat-back, and hence may be 60 made in any shape or form that will properly guide the sliding bracket *E*. Once the motion of the back begins the weight thereof is almost wholly removed from the brackets *E*, and consequently they slide with great freedom.

K represents handles set into the side or 65 sides of the seat-back for shifting the back.

These handles are preferably arranged as close to the sliding brackets and upper end of the rocking arms *D* as convenient for the hand 70 and yet avoid striking the arm of the seat next to the aisle. If desired, a handle *K* may be placed only on the aisle side of the seat-back; but by having such a handle on both ends the seat-back may be set upon the arms 75 *E'* with either end toward the aisle. The use of this handle *K* enables the back to be reversed without requiring the hand to grasp the upholstery, and hence avoids undue wear thereof. A further use of this handle in its 80 low position is to enable the power to be so applied to the upper end of the rocker-arms *D* as to make them move freely, said result being secured by an upward and transverse pull upon the handle. In this way the angle 85 of the arms *D* may be so oblique at the extreme positions of the back that they act somewhat as locks to prevent the too free shifting of the back. This result may be secured, if desired, by the proper designing of 90 the parts. It has the advantage of preventing the shifting of the back when a person in the rear seat puts his knees against the back or otherwise puts a forward pressure upon it 95 unintentionally and also of preventing too ready reversing of the backs by the passengers by making them believe that the back is locked in position.

While some railroad companies desire that the seats shall be reversed easily, others desire the use of locks to prevent the passengers from reversing the seats or some means to prevent the too ready reversal at the start. This latter feature may be excellently secured 100 by the use of my invention, because the resistance to starting the movement of the seat-back may be made sufficient to secure the desired effect upon the passengers.

The space between the cushion and end frames is undesirable in that it offers an opportunity for articles to slip down and become lost or to clog the working parts. To overcome this objection, I provide automatic lids *I* for closing said space from above. These lids are preferably divided into three 110 parts and hinged at *i*, so as to fall when left to themselves. To insure their closing positively, I prefer to provide a small spring *J*, adapted to snap the lids down or horizontal when released. One of these lids is always 115 held up by the sliding brackets *E*, as shown, and during its travel it will sometimes hold two of the lids up. The brackets act as cams for raising and releasing the lids. Any other suitable means may be employed to operate 120 the lids in place of the brackets *E*, as, generically considered, it is immaterial to my invention how they are operated.

While I prefer the constructions shown as being excellently adapted for the purposes of 125 my invention, I do not confine myself thereto, as the details may be modified without departing from the spirit of the invention.

Having now described my invention, what

I claim as new, and desire to secure by Letters Patent, is—

1. In a car-seat, the combination of the main frame, transversely-adjustable guide-brackets at each end having guide-arms at their upper parts, a seat-back adjustably supported upon the guide-arms and movable with the guide-brackets, rocker-arms pivoted to the main frame and adjustably connected with the seat-back so as to raise the seat-back on the guide-arms and then lower it during its reversal.

2. In a car-seat, the combination of the main frame, transversely-adjustable guide-brackets at each end having guide-arms at their upper parts, a seat-back adjustably supported upon the guide-arms and movable with the guide-brackets, rocker-arms pivoted to the main frame and adjustably and detachably connected with the seat-back so as to raise the seat-back on the guide-arms and then lower it during its reversal.

3. In a car-seat, the combination of the main frame, transversely-adjustable guide-brackets at each end having guide-arms at their upper parts, a seat-back adjustably supported upon the guide-arms and movable with the guide-brackets, rocker-arms pivoted to the main frame and adjustably connected with the seat-back so as to raise the seat-back on the guide-arms and then lower it during its reversal, and a rock-shaft connecting the rocker-arms at each end of the main frame whereby they move in unison.

4. In a car-seat, the combination of the main frame, transversely-adjustable guide-brackets at each end having guide-arms at their upper parts, a seat-back adjustably supported upon the guide-arms and movable with the guide-brackets, rocker-arms pivoted to the main frame and adjustably connected with the seat-back so as to raise the seat-back on the guide-arms and then lower it during its reversal, a shifting seat-cushion, and means connecting said cushion with the rocker-arms whereby the cushion is shifted when reversing the back.

5. In a car-seat, the combination of the main frame, transversely-adjustable guide-brackets at each end having guide-arms at their upper parts, a seat-back adjustably supported upon the guide-arms and movable with the guide-brackets, rocker-arms pivoted to the main frame and adjustably connected with the seat-back so as to raise the seat-back on the guide-arms and then lower it during its reversal, seat-cushion-supporting arms having cam portions and a vertical slot, a seat-cushion supported upon said cushion-supporting frames, and transverse pins extending through the vertical slots of the seat-cushion-supporting frames and connected with the rocker-arms, whereby the seat-cushion is simultaneously shifted when reversing the seat-back.

6. In a car-seat, the combination of the main frame having transversely-arranged guides

at each end, guide-brackets adjustably supported upon said guides, a seat-back carried by said guide-brackets with provision for vertical adjustment, and rocker-arms pivoted to the main frame and having their free ends movably connected with the seat-back whereby the latter is elevated relatively to the transverse guides for the brackets during its reversal.

7. In a car-seat, the combination of the main frame having transversely-arranged guides at each end, guide-brackets adjustably supported upon said guides, a seat-back carried by said guide-brackets with provision for vertical adjustment, rocker-arms pivoted to the main frame and having their free ends movably connected with the seat-back whereby the latter is elevated relatively to the transverse guides for the brackets during its reversal, and a handle secured to the end of the seat-back adjacent to its connection with the rocker-arms and guide-brackets whereby the back may be pulled upward at substantially right angles to the rocker-arms in starting the motion for reversal.

8. In a car-seat, the combination of the main frame, a shifting seat-back, guiding devices for guiding the seat-back while being shifted and supporting it in an upright and proper angular position, supporting devices for lifting the seat-back on its guiding devices during its reversal, and a handle arranged upon the end of the seat-back near its lower part so as to assist in lifting the back when in the act of pulling it in reversing.

9. In a car-seat, the combination of the main frame, a transversely-movable guide-bracket having a laterally-arranged upwardly-directed guide-arm, a seat-back having an upright socket opening through the lower edge at a distance from the end and wholly within the upholstery adapted to receive the guide-arm, and a supporting-arm pivoted to the main frame and having its upper end extending through the bracket and supporting the seat-back at its side edge outside of the socket.

10. In a car-seat, the combination of the main frame, transversely-movable guide-brackets having upwardly-directed guide-arms connected thereto by slotted horizontal portions, rocker-arms pivoted to the main frame and projecting upward through the slotted horizontal portions of the guide-brackets, and a jointed connection between the upper ends of said rocker-arms and the seat-back.

11. In a car-seat, the combination of the main frame, the seat-cushion, a movable seat-back, upwardly-extending supporting parts for supporting the seat-back and movable between the cushion and end frame of the main frame, and adjustable lids hinged to the main frame and adapted to fold down to close the space between the end frame of the main frame and the seat-cushion.

12. In a car-seat, the combination of the main frame, the seat, a movable seat-back,

upwardly-extending supporting parts for supporting the seat-back and movable between the cushion and end frame of the main frame, and spring-actuated adjustable lids hinged to the main frame and adapted to fold down to close the space between the end frame of the main frame and the seat-cushion and also adapted to be raised or lowered by the supporting devices for the seat-back during their travel.

13. In a car-seat, the combination of the main frame, the seat-cushion, the seat-back, a series of adjustably-connected lids arranged between the end of the main frame

and the seat-cushion, and supporting devices 15 for the seat-back adapted to be moved between the cushion and end frame of the main frame for moving the lids so as to permit said devices to pass during the reversal of the seat and the lids to be closed when clear of 20 the said seat-back-supporting devices.

In testimony of which invention I have hereunto set my hand.

HENRY S. HALE.
